CLAIM

The ornamental design for a waste receptacle, as shown and described.

DESCRIPTION

FIG. 1 is a top perspective view of a waste receptacle showing my new design;

FIG. 2 is a top plan view thereof;

FIG. 3 is a front elevational view thereof, it being understood that the rear elevational view, right side elevational view and left side elevational view are identical thereto;

FIG. 4 is a bottom plan view thereof; and,

FIG. 5 is a right perspective view in an exploded condition thereof.

Fig. 1
